UNITED STATES PATENT OFFICE.

JOHN J. COLL, OF RENO, NEVADA.

VALVE.

1,152,604.

Specification of Letters Patent. Patented Sept. 7, 1915.

Application filed March 19, 1914. Serial No. 825,827.

To all whom it may concern:

Be it known that I, JOHN J. COLL, a citizen of the United States, residing at Reno, in the county of Washoe and State of Nevada, have invented certain new and useful Improvements in Valves, of which the following is a specification.

My invention relates to valves, and with regard to certain more specific features thereof to air valves associated with the carburetor of internal combustion engines, although it is to be understood that it is of course capable of other applications.

One of the objects of the present invention is to provide a simple and practical valve capable of quick, accurate and convenient adjustment under varying conditions.

A further object is to provide a commercially practical valve especially adapted for use with carburetors for internal combustion engines which will be cheap to manufacture.

A further object is to provide a highly efficient valve of the above character capable of both automatic and manual adjustment.

The invention accordingly consists in the features of construction, combination of elements and arrangements of parts which will be exemplified in the device hereinafter described, and the scope of the application of which will be indicated in the following claims.

In the accompanying drawings wherein is shown one of various possible embodiments of the invention, Figure 1 is a vertical sectional view of the valve in closed position; Fig. 2 is a similar view with the valve in automatic open position; Fig. 3 is a similar view with the valve wide open; Figs. 4, 5 and 6 are transverse sectional views taken on the lines 4, 4, 5, 5, and 6, 6, respectively of Fig. 2; Fig. 7 is a sectional perspective view of one of the parts.

Similar reference characters denote corresponding parts in the several views.

Before describing the present invention in detail it may be briefly stated that the valve illustrated in the accompanying drawing will be hereinafter described with reference to its application to the internal combustion engine of an automobile.

The valve is preferably positioned adjacent the dash-board of the vehicle and un-

der the hood in either upright or horizontal position, and has one end connected with the manifold of the gas engine at a point immediately above the carburetor. The valve is operated and controlled by means of a flexible wire or light cable leading from the valve stem to an actuating member or lever adjacent the steering wheel, in convenient reach of the operator, in such manner that it may be quickly operated and locked in adjusted position at any desired point. As these features are all well known to those familiar with the art, it is believed that a detail illustration and discussion thereof is unnecessary.

Referring now to the accompanying drawing, and more particularly to Fig. 1, 10 denotes a valve casing, which may be made in one or two parts, as desired, although a single integral casing as herein shown is believed to be preferable on account of its cheapness of manufacture. This valve casing is divided into two chambers, and in the present modification will be referred to as the outer chamber 11 and the inner chamber 12. These chambers it will be noted are slightly different in diameter and form a central intermediate shoulder 13. Immediately above this shoulder are provided a plurality of openings or air inlets 14. At the bottom of the casing is a threaded nut 15 coaxing with the inner wall of the casing at a point 16, and provided with internal threads 17, where it may be connected by means of a suitable pipe to the manifold of the gas engine. This nut 15 has an upwardly projecting portion 18 of slightly larger diameter than the threaded portion 17, thereby to provide a seat for a spiral spring 19 supporting a piston 20. The upper central part of this piston is provided with a valve seat 21, which co-acts with a cone-shaped needle 22, formed on the lower end of valve stem 23. The valve stem is also provided with an enlarged portion 24, adapted to slide in the upper chamber of casing and to maintain the needle in a position concentric with the valve-seat of piston. The upper part of this enlarged portion 24 forms a seat for one end of a coil spring 25, the opposite end of which bears against the closed end of the casing. The upper part of the stem 23 has an opening or eyelet 27, to which is connected a wire

or cord leading to the operating lever. This constitutes a means for manually adjusting the valve, as will be hereinafter explained.

The piston 20, as shown more clearly in Fig. 7, is provided with a reduced portion 28, and openings or cut away portions 29. This construction will reduce the friction of the piston as it slides back and forth in the casing, and also permits the dust, dirt, or lubricant which might otherwise collect therein to escape into the casing.

It is well known to those familiar with the art, that in order to obtain complete combustion of gasolene a proper proportion of air is required. It is also well known that the action of automatic air valves becomes more or less impaired proportionately as they raise or lower in altitude, and that it becomes necessary to change the adjustment of the valves to correspond with the changes of altitude, and for this and other reasons I have devised a valve herein described that may be adjusted quickly and accurately, so as to advance or retard the supply of air to the degree desired, without the necessity of adjusting screws or removing parts to gain access to the carbureter. The valve is not only automatic in its action, but may also be manually opened to admit the free admission of air through the piston. This feature is illustrated in Fig. 3. Or it may be closed entirely so as to prevent the admission of air. This feature of the valve is illustrated in Fig. 1.

The operation of the valve is substantially as follows: Before starting the engine the valve is adjusted to a closed position by means of lever adjacent to steering-wheel, heretofore mentioned. In this position the supply of air is limited, and a rich mixture of gas usually desired in starting is obtained. When a greater amount of air is required, the valve stem 23, is gradually raised by means of said lever, and rested at a point found to be the proper adjustment. Proportionately as the stem is raised or lowered the tension of the valve spring 19 is increased or decreased. This increase or decrease of spring tension governs the automatic movement of the valve piston. The cone shaped end of stem 23 regulates the amount of air permitted to pass through the valve opening in the upper end of the piston.

While the valve is shown in vertical position in the drawing it is obvious that it may be arranged horizontally with relation to the dash board of the vehicle.

The coil-spring 25 situated in the upper chamber of valve is made so as to embody strength sufficient to force the stem down to a closed position of the valve, and by this means the stem is carried down to any desired point of adjustment, proportionately as the said lever is released and per-

mitted to move back. It is thus seen that the present invention provides a simple and practical automatic air intake valve particularly adapted for use with internal combustion engines of motor vehicles.

Having thus described my invention what I claim as new and desire to secure by Letters Patent is—

1. In a valve mechanism, in combination, a casing having an inner chamber and an outer chamber, a hollow piston forming a fluid passage and provided with a valve seat in its upper end and adapted to move in the inner chamber, a spring extending within the piston and adapted to actuate the same, and a collar formed at the junction of said chambers adapted to limit the upward movement of said piston.

2. In a valve mechanism, in combination, a casing having an inner chamber and an outer chamber, a hollow piston forming a fluid passage and provided with a valve seat in its upper end and adapted to move in the inner chamber, a collar formed at the junction of said chambers adapted to limit the upward movement of said piston, a nut adapted to close the lower end of the inner chamber and having an upwardly extending central portion forming a seat, and a spring extending within the piston and seated at its lower end on the extended central portion of the nut.

3. In a valve mechanism, in combination, a casing having an inner chamber and an outer chamber, a hollow piston forming a fluid passage and provided with a valve seat in its upper end and adapted to move in the inner chamber, a collar formed at the junction of said chambers adapted to limit the upward movement of said piston, a nut adapted to close the lower end of the inner chamber provided with an internal threaded portion adapted to co-act with means to connect the valve to the engine and having an upwardly extending central portion forming a seat, and a spring extending within the piston and seated at its lower end on the extended central portion of the nut.

4. In a valve mechanism, in combination, a casing having an inner chamber and an outer chamber, a hollow piston forming a fluid passage and provided with a valve seat in its upper end and adapted to move in the inner chamber, a spring extending within the piston and adapted to actuate the same, and a collar formed at the junction of said chambers adapted to limit the upward movement of said piston, a slidably mounted stem adjustably mounted in the outer chamber and having a cone-shaped lower end adapted to engage the valve seat in said piston.

5. In a valve mechanism, in combination, a casing having an inner and an outer chamber, a hollow piston forming a fluid

passage and having a valve seat and adapted to move in the inner chamber, a collar intermediate said chambers forming a stop to limit the upward movement of said piston, 5 air inlets in the casing above said collar, a spring extending within the piston and adapted to force the same upwardly, a slide-
able stem mounted in the outer chamber and provided with a cone-shaped lower end 10 adapted to engage the valve seat in the piston and having its opposite end extending through the upper end of said outer chamber, and a spring surrounding said stem and adapted to cause its lower end to seat 15 in the piston, and manually operated means for adjusting the tension of said spiral spring.

6. In a valve mechanism, in combination, a casing formed with an inner and an outer chamber, a hollow piston forming a fluid 20 passage and adapted for vertical movement in said inner chamber and formed with a reduced wall intermediate its ends and with openings through the lower portion of said wall, whereby to reduce friction and to prevent the accumulation of matter between it and the surrounding wall of the inner chamber. 25

In testimony whereof I affix my signature in presence of two witnesses.

JOHN J. COLL.
